United States Patent Office

Des. 229,808
Patented Jan. 8, 1974

229,808

TABLE OR THE LIKE

Ronald J. McDonald, 201 E. 61st St.,
New Rochelle, N.Y. 10021

Continuation of design applications Ser. No. 18,144 and
Ser. No. 18,152, both June 18, 1969, and Ser. No.
20,723, Dec. 31, 1969. This application Apr. 20, 1970,
Ser. No. 22,536

Term of patent 14 years

Int. Cl. D6—03

U.S. Cl. D6—177

FIG.1

FIG.2

FIG.3

FIG.4

FIG.5

FIG.6

FIG.7

FIG.8

FIG. 9

FIG. 10

FIG. 11

FIG. 12

FIG. 1 is a perspective view of a table showing my new design wherein the top is transparent and the base is opaque;

FIG. 2 is a plan view;

FIG. 3 is a view in side elevation;

FIG. 4 is an end view thereof;

FIG. 5 is a perspective view of the table shown in FIG. 1 wherein the top is opaque and the base is transparent;

FIG. 6 is a plan view;

FIG. 7 is a view in side elevation;

FIG. 8 is an end elevational view thereof;

FIG. 9 is a perspective view of the table shown in FIG. 1 but wherein both the top and base are formed of transparent material;

FIG. 10 is a plan view;

FIG. 11 is a view in side elevation; and

FIG. 12 is an end elevational view thereof.

This application is a continuation of my earlier filed applications Ser. Nos. D.18,144 and D.18,152 filed June 18, 1969 and D.20,723 filed Dec. 31, 1969, all now abandoned.

I claim:

The ornamental design for a table or the like, as shown and described.
